(57) **CLAIM**

The ornamental design for a base unit, as shown and described.

DESCRIPTION

In a preferred embodiment the nature of this product is as a base unit that facilitates heating a portion of a container of shaving cream, lotion or other personal care liquid.

FIG. 1 is a left, top, frontal perspective view of a base unit embodying our new design;

FIG. 2 is a front elevational view thereof;

FIG. 3 is a right side elevational view thereof;

FIG. 4 is a left side elevational view thereof;

FIG. 5 is a top plan view thereof;

FIG. 6 is a bottom plan view thereof;

FIG. 7 is a rear elevational view thereof;

FIG. 8 is a view similar to FIG. 1, but of a second embodiment;

FIG. 9 is a front elevational view thereof;

FIG. 10 is a right side elevational view thereof;

FIG. 11 is a left side elevational view thereof;

FIG. 12 is a top plan view thereof;

FIG. 13 is a bottom plan view thereof; and,

FIG. 14 is a rear elevational view thereof.

The broken line representations of an electrical control button and a status light in FIGS. 1-5, of a plug attachment notch in FIGS. 1, 4, 6 and 7, of support feet in FIGS. 2-4, 6 and 7, of surface ornamentation in FIGS. 1-4 and 7, and various vent holes in FIG. 6, are for purposes of illustration only and form no part of the claimed design.
